UNITED STATES PATENT OFFICE.

RICHARD FRANCIS JOYCE, OF HAVERHILL, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR AND METHOD OF HEEL-SEAT FITTING.

Application filed September 23, 1919. Serial No. 325,760.

This invention relates to the manufacture of shoes and is illustrated herein with reference to the heel-seat fitting operation performed preparatory to the attachment of 5 wood heels to shoes.

Wood heels are commonly formed with a cupped or concave attaching surface, the periphery of which directly engages the upper of the finished shoe so that the margin of 10 the sole does not show between the heel and the upper. To permit this and to provide a secure anchorage for the wood heel, it is the practice to reduce the heel-seat of the sole by removing surplus material from the 15 peripheral portion thereof, the heel-seat being at the same time beveled so as to conform to the cupped attaching surface of the wood heel. A pair of shoulders are commonly formed also at the heel-breast line to 20 engage the breast of the heel.

It is essential to good shoemaking that the heel-seat fitting operation, which is sometimes spoken of as "cutting on" the heel, should be performed with a considerable 25 degree of accuracy. If insufficient stock is removed from the sole, it is impossible to bring the edge of the heel into close contact with the shoe upper and a neat appearance cannot be obtained. If too much stock 30 is removed, a secure anchorage for the heel cannot be obtained and the shoe is weakened. Moreover, it is necessary that the breast cuts be made at exactly the right place. If they 35 are too far to the rear, the heel will be placed further back than it should be and the lines of the shoe will be spoiled. If the breast cuts are too far forward, the heel will be placed too far forward, thereby spoiling the 40 lines of the shoe, or there will be a gap between the breast of the heel and the sole, and this, of course, cannot be permitted.

Prior to the present invention the heel-seat fitting operation has usually been performed by hand. The workman takes the 45 wood heel which is to be attached to the particular shoe he is to operate upon, places it on the sole of a shoe in the position which he judges it should occupy in the finished shoe, and marks the location of the heel-breast line upon the sole of the shoe. Thus he uses the heel itself as a gage or templet to locate the heel-breast line. After removing the heel from the shoe, he trims off the surplus stock with a knife, making the heel-

breast receiving cuts approximately at right 55 angles to the surface of the sole and beveling the periphery of the heel-seat as he removes the surplus stock therefrom. In performing this operation by hand, a good workman of considerable experience and judgement has no great difficulty in locating the breast-receiving cuts approximately where they should be, but an inexperienced man will cut a good many of them out of place. The trimming operation, moreover, that is 60 to say the beveling and removal of the surplus stock from the periphery of the heel-seat, as done by hand, is hard work and is consequently expensive. Moreover, since a wood heel cannot be attached to a shoe if 65 insufficient stock is trimmed from the periphery of the heel-seat of the sole but can be attached, though not as securely as it should be, if too much stock is removed, there is always a tendency on the part of 70 the workmen to remove more stock than they should.

With these circumstances in view, it is an object of the present invention to provide an improved method of and machine for 75 heel-seat fitting, which will make it possible even for inexperienced and unskilled workers to perform the heel-seat fitting operation easily and expeditiously, and therefore at a small expense, and with assurance of accuracy.

In its method aspect the invention insures accurate control of the fitting operation by gaging the forward extent of the trimming 80 operation from a heel such as is to be attached to the particular shoe operated upon, located in a predetermined position at a substantial distance from the heel-seat of the shoe. This method, which is particularly 85 adaptable to machine operation, is disclosed herein with reference to a heel-seat fitting machine, which, as illustrated, constitutes a preferred embodiment of the invention in 90 its machine aspect. This machine, in accordance with features of the invention, is 95 provided with shoe-positioning means and a cutter arranged for relative movement to cause the cutter to trim surplus material from the peripheral portion of the heel-seat of a shoe positioned by said means, the extent of the relative movement being controlled or gaged through suitable connections 100 from a heel located at a predetermined posi-

tion a substantial distance from the heel-seat of the shoe. As illustrated, the heel which thus serves to control the extent of the trimming operation is placed between a pair of gage members which are mounted 5 for relative movement so that one of them may engage the rear and the other the breast of the heel, the position of one of these members relatively to other parts of the machine controlling the extent of the trimming operation.

Since some wood heels are made as rights and lefts, being longer upon the outer side than upon the inner side, provision is made 15 in the illustrated machine for controlling the trimming cut accordingly; that is to say, if such a heel is to be attached to the shoe and is accordingly used to control the heel-seat fitting operation, the forward extent of 20 the trimming upon the two sides of the heel-seat will be unsymmetrical to the same extent that the heel itself is unsymmetrical, extending further forward on the outer edge than on the inner edge of the sole of the shoe.

25 In accordance with other features of the invention, the herein disclosed machine is provided with shoe-positioning means, including a crease plate arranged to enter the rand crease of a shoe, and a chop knife, the shoe-positioning means and the knife being arranged to permit relative movement of the knife and the shoe operated upon peripherally of the heel-seat of the sole of the shoe to cause the knife to trim surplus material 30 from the heel-seat of the sole. As the path of movement of the knife is inclined relatively to the surface of the sole, the heel-seat is at the same time beveled and rendered convex to correspond with the concave attaching surface of the sole. The knife of 40 the illustrated machine, in accordance with a further feature of the invention, is provided with a plurality of angularly related cutting edges so that the surplus material is removed in the form of a succession of chips, the heel-breast cuts being made by edges of 45 the knife positioned approximately at right angles to the edge of the sole.

While the invention has been disclosed 50 herein particularly with reference to the heel-seat fitting operation, it should be understood that this disclosure is illustrative and that the invention in its machine aspect is not limited to a machine for performing this operation, since in various of its aspects the invention is useful in connection with the performance of other operations.

With the above and other objects and features in view, the invention will now be 60 described in connection with the accompanying drawings and pointed out in the claims.

In the drawings,

Fig. 1 is a side elevation of a preferred embodiment of my invention;

65 Fig. 2 is a front elevation thereof;

Figs. 3 and 4 are detail views on an enlarged scale of the knife and the holding means therefor;

Figs. 5 and 6 are similar views of the 70 knife alone;

Fig. 7 is a horizontal section at the line 7-7 of Fig. 1;

Fig. 8 is a detail sectional view (at line 8-8 of Fig. 1) of the base portion of the 75 jack;

Fig. 9 is a detail view of the jack guiding plate;

Figs. 10 and 11 are detail sectional views on an enlarged scale, of the edge portion of the knife, and the crease guide or plate;

Fig. 12 is an enlarged detail plan view of the crease guide or plate;

Fig. 13 is a central vertical sectional view at the line 13-13 of Fig. 7;

Figs. 14 and 15 are detail plan and sectional views of a clutch mechanism which I employ;

Fig. 16 is a horizontal sectional view, similar to Fig. 7, showing the parts in different position;

Fig. 17 is a vertical sectional view, similar to Fig. 13, showing the table in work-receiving position;

Fig. 18 is a bottom view of a shoe sole, 90 which has been "cut on" or fitted;

Fig. 19 is a side view, partly in section, of the heel portion of the shoe, showing the heel in position thereon after the heel-seat has been fitted.

The removal of surplus material at the 100 edge of the heel-seat of the sole of a shoe is accomplished in the machine to be herein described by means of an oscillating chop knife 38 (Fig. 1) moving in a fixed path at an acute angle to the tread surface of the sole. The work is mounted upon a supporting jack 50 movable in a horizontal plane upon the machine to present the various parts of the heel end of the shoe to the tool and to cause the removal, by successive cuts of the oscillating knife, of a horseshoe-shaped section of surplus material extending from the heel-breast line rearwardly around the rear of the shoe and forward to the heel-breast line at the other side of the shoe. The trimming operation is controlled by means of a crease plate or guide 46 positioned adjacent to the knife to enter the rand crease of the shoe and a heel-measuring device 78 (Fig. 16) movable with the shoe and arranged to start and to terminate the operation of the machine at the desired points.

As shown in the drawings, the base 2 of the machine is provided with parallel guide ways 2^a (Fig. 2) within which a table 4 is mounted to slide toward and from the front of the machine, and manually operated means are provided for moving the table in and out, so that the work may be placed in position and removed conveniently, said 120

means comprising an oscillatory shaft 6 (Fig. 1), having a hand lever 8, for operating it, and a gear 10 (Fig. 17), which is arranged in mesh with a rack 12 on the under side of the table 4. An upright frame 14 is secured on said base in the rear of said table, the upper portion thereof being bifurcated (Fig. 2). A main shaft 16 is journaled in said upright frame 14 and is constantly driven by a pulley 18, and an auxiliary shaft 20 (Figure 1) is journaled in the base and driven from said main shaft by means of pulleys 22 and 24 and a belt 25. The shaft 16 is provided with an eccentric, 15 to which an eccentric rod 28 is connected and the opposite end of said rod is connected to an oscillatable knife carrying lever 30, which is mounted on a pivot 32, supported in a block 34, arranged to be vertically adjusted in a slot formed in the upper end of the frame by means of adjusting screws 36. The trimming or fitting operation is accomplished by successive cuts made by a channel-shaped, oscillating chop knife or 25 cutter 38 acting to remove surplus material chip by chip from the edge of the sole from the heel-breast line rearwardly around the periphery. This knife or cutter is carried by the lever 30 which extends forwardly and 30 obliquely downward from its pivot and is provided with a rectangular-shaped projection 30^a (Fig. 4) at its end, on which the channel-shaped knife 38 is mounted. As shown in Figs. 3 to 6, said knife is formed 35 to provide three cutting edges, 38^a, 38^b and 38^c, arranged contiguously and at right angles to each other successively, the edges 38^a, 38^c, being arranged at right angles to the intermediate edge 38^b, at its opposite ends. Thus this cutter, turning on an axis, is provided upon each side with radial cutting edges acting in planes transverse to the pivotal axis of the cutter. The cutter is also provided with an outer cutting edge disposed 40 lengthwise of this axis and traveling in a path between the paths of the side cutting edges so that the surplus stock is removed chip by chip. The shank portion of the knife is correspondingly formed, so that its 45 side and bottom portions form a right angular groove in which the end portion of the projection 30^a is adapted to fit, the face at the end of said projection being at approximately right angles to the lever arm, so that the knife will be held on the lever in a right- 50 angular position relative thereto. Clamping plates 40 are bolted to opposite sides of the lever arm, to clamp the sides of the knife against said projection 30^a and said knife is provided with a threaded lug 38^d, adapted 55 to receive an adjusting screw 42, the head of which is swiveled in a bracket 44 (Figs. 2 and 3), secured to the lever arm, so that said knife may be adjusted longitudinally. A screw 41, extending between the plates 40, 60 passes through a slot 43 in the sides of the knife and, when tightened, firmly clamps the knife in adjusted position. The sides and bottom of said knife are integral and their cutting edges are beveled on their inner sides 70 (Figs. 10 and 11), the intermediate cutting edge 38^b extending transversely of the shank portion of the knife.

In order to support the edge of the sole and to assist in positioning the work with 75 respect to the cutting path of the knife 38, a crease plate or guide 46 having a tapered edge to enter the rand crease of the shoe, is mounted on a bracket 48, which is secured to the frame 14, and on which it is horizontally adjustable. The upper surface of the guide 46 is horizontal, and the arrangement is such that, when the lever 30 is oscillated, the knife will be reciprocated, or vibrated approximately longitudinally along a path 80 oblique to the tread surface of the sole to cut through the periphery and form a bevel around the heel-seat. At the end of its down stroke, the knife edges will be positioned in the plane of the horizontal surface 90 of the guide, and, at the points where the knife edges would engage said surface, a correspondingly shaped recess 46^a is formed (see Fig. 12), so that the knife edges may be moved into the plane of the surface of the 95 guide, without any actual engagement there with such as would tend to dull the knife. This recess is also formed to permit a slight shearing action at the finish of the stroke, so that the chip will be completely 100 severed. The extreme edge of the guide is circular except at the portion in proximity to the intermediate portion of the recess which receives the bottom or intermediate portion of the knife edge, at which portion it is provided with a straight portion 46^b, which is in close proximity to, parallel to, and of the same length as said intermediate portion of the recess, as shown in Figs. 10, 11 and 12. 105

To provide relative movement of the shoe 110 and the knife so as to transfer the point of operation around the periphery of the heel-seat portion of the sole, the shoe is supported for movement to bring the peripheral portion of the heel-seat of the sole of the shoe 115 into the path of movement of the knife. To this end, a jack 50, having a flat base, is movably supported, partly on the horizontal surface of the table 4, and partly on a guiding plate 52 (Figs. 9 and 17), of oblong 120 form, which is arranged in a recess in the table, so that its upper surface is flush with the surface thereof. A T-shaped tongue 50^a (Figs. 13 and 17) is formed on the bottom of the base of the jack 50, which is slidably engaged with a correspondingly shaped slot formed in the upper surface of the plate 52, so that the only relative movement permitted therebetween is a longitudinal sliding movement. The plate 52 is provided on its under 125 130

side with a stud 52^a (Figs. 9 and 13), which is rotatably mounted in a recess or aperture formed in the table, and the ends of the plate 52 are curved on arcs having said stud 5 as a center. Said stud 52^a is located substantially nearer one end of the plate 52 than the other and the side of the recess in the table, in which the plate is located, is also curved about the center of the stud 10 (Fig. 7). The rear end of the jack base is formed on a curved line which corresponds approximately to the outline of the heel end of a shoe, and a gear rack 50^b (Fig. 8) is formed thereon, which extends from a point 15 at one side about the rear of the base to a corresponding point at the other side.

A vertical shaft 54 (Fig. 17) is journaled in the rear end of the table 4 and is provided with a gear 56 at its upper end, which is 20 arranged in mesh with the gear-rack 50^b on the jack, and the lower end of said shaft is provided with a bevel gear 58, which is arranged in mesh with a bevel gear 60, mounted on a sleeve 62, the latter being journaled 25 in a depending portion 4^b of the table and held from longitudinal movement therein. A shaft 64 is journaled in the machine base 2 and the sleeve 62 is splined on said shaft, so that the table may be moved forwardly 30 and rearwardly and a driving connection maintained between the shaft 64 and the gear-rack 50^b on the jack.

A bevel gear 66 is secured on the rear end of shaft 64 and arranged in mesh with a 35 pair of bevel gears 68 and 70 (Figs. 14 and 15), which are mounted to rotate freely on the shaft 20, a clutch sleeve 72 being splined on the shaft 20 between said gears 68 and 70 and movable into driving engagement 40 with either, to cause opposite rotation of shaft 64. An operating lever 74 for said sleeve 72 is pivoted on the machine base with its upper end arranged in engagement with a lever 76, the rear end of which is 45 pivoted at 77 (Figs. 13 and 16) to the upright frame 14, said lever 76 having arms 76^a, 76^b, at its front end. A cross bar 78 is mounted on an adjusting screw 80 in the jack base in position to engage the arms 76^a, 50 76^b, as hereinafter explained.

Manually controlled means for operating the lever 76, are also provided, comprising a link 82 (Fig. 16), which is connected to said lever 76 and to a bell-crank lever 84, the 55 latter being also connected by a link 86 to an operating lever 87 (Fig. 1).

Accurate control of the heel-seat fitting operation in the machine of the present invention is secured by the provision of a heel-measuring device located upon and movable with the jack 50 and of connections between said measuring device and the operating parts of the machine to terminate the operation of the machine at points corresponding to the position of the heel-breast line in

the finished shoe. The measuring device comprises a fixed abutment 88 arranged to co-operate with the cross-bar 78 to measure a heel, said cross-bar being arranged to engage the clutch operating means as above suggested when, in the relative traversing movement of the shoe and the cutting knife, the knife operates at a position corresponding to the position of the heel-breast line. 70

This shoulder 88 (Figs. 1, 13 and 16) is located on the base portion of the jack at its rear end, and, before a heel (or one of a number of heels having the same base length) is attached to the shoe, the heel is placed on the base of the jack with its rear 80 end against said shoulder, and then the bar 78 is adjusted so that its edge bears against the breast of the heel. The jack is provided with a form or extensible last 90, on which the shoe to be operated on is placed. 85

In placing the shoe on the last, the table is moved out from its rear position by means of the hand lever 8 and then is moved back so that the edge of the guide 46 engages the rand, crease of the shoe. In starting the 90 operation, the jack will be in a position side towards the front, as in Fig. 16, and the clutch sleeve 72 will be in a neutral position midway between the gears 68, 70. The knife 38 will be rapidly vibrated, so that, 95 when the shoe is moved back against the crease guide 46, the knife will remove a chip at the edge of the sole on a bevel, as indicated in Figs. 10 and 11, and, because of the angularly related cutting edges of said knife, 100 it will also form a shoulder at the heel-breast line.

When the machine is driven, the shaft 20 is rotated constantly in the direction indicated by the arrow in Fig. 1. 105

Assuming the jack is in the position of Fig. 16, the operator will then push the handle of lever 87 rearwardly, causing the lever 76 to be moved to the position shown in Fig. 7, this movement causing the clutch sleeve 72 to be thrown into engagement with gear 68, thereby causing rotation of gear 56 in the direction indicated by the arrow thereon in Fig. 7. This rotation will first cause a sliding movement of the jack to the right, 110 on the plate 52 as allowed by the tongue 50^a, through the engagement of the gear 56 with the side portion of the gear rack 50^b, so that the shoe will be moved past the knife, which will remove additional chips, as the shoe is fed, further to bevel the periphery of the heel-seat portion of the sole. As soon as the gear 56 engages the rounded portion of the gear rack 50^b, the jack 50 and the plate 52 will begin to swing together about the pivot 52^a and this movement will continue until the opposite side portion of the rack 50^b is engaged, whereupon the jack will be moved to the right again. When the point is reached at which the cutting operation 115 120 125 130

should be finished, one end of the bar 78 will engage the arm 76^a of the lever 76, and move the same sufficiently to cause the clutch sleeve to be thrown out of engagement, so 5 that the feeding movement is arrested. On account of the shape of the knife 38, or the provision of the side blades, a square shoulder will be formed at each end of the cut, against which the heel breast will bear when 10 in position on the shoe and the sole edge portion will be removed to permit close contact of the concave attaching surface of the heel with the heel-seat of the sole and so that the periphery of the heel will seat on the shoe 15 upper.

During the operation above described the shoe is held against the crease plate or guide 46, the table being moved inward or outward, as it is turned, according to the configuration 20 of the shoe, the jack thus having universal movement in a horizontal plane, in so far as may be necessary to present the shoe in the proper position for engagement with the knife, in performing the heel-seat fitting 25 operation.

The shoe may be held yieldingly in engagement with the crease guide 46 by means of the hand lever 8, or a weight 92 may be attached to the rear end of the table by 30 means of a cord or chain 94 passing over a pulley 96 (see Fig. 13), which will act automatically to hold the shoe against the guide with the desired force during the feeding movement of the jack.

35 When the operation on one shoe is finished, the jack will be in the opposite position to that in which it was at the beginning of the operation, and when the next shoe is to be operated on, the jack will be moved out, 40 while in this last position, and the shoe which has been operated on will be removed and another placed on the jack. The jack will then be moved back and the above described operation repeated. When starting the operation with the jack in the opposite position to that of Fig. 16, the starting lever 86 will be pulled outward, so that, instead of having the gear 68 engaged by the clutch sleeve 72, as on the previous operation, the gear 70 will 45 be engaged by said sleeve, causing opposite rotation of the gear 56, and, therefore, opposite movement of the jack. When the operation is finished, the opposite end of the bar 78 will engage the arm 76^b of the lever 76, 50 moving the clutch sleeve to the neutral position, and stopping the feeding movement.

When the adjustment of the bar 78 is changed for a heel having a base of different length, the above described operation will 55 be somewhat varied. It will be observed that when the bar 78 moves the lever 76 from one extreme position to the neutral position, the bar will prevent the lever from being drawn back to such extreme position 60 by the starting lever 87, so that, to start the feeding operation at all, the lever 87 must be moved so as to move the lever 76 to the opposite extreme position. If, however, the bar 78 is moved away from the shoulder 88, to provide for a heel having a longer base 65 than that for which the bar was previously adjusted, the jack being in the dotted line position of Fig. 7, or the position of Fig. 16, the starting lever would then be moved back to the position from which it was thrown 70 by the bar 78, when the lever 76 was last thrown to neutral position. The feeding operation would then be started, and almost immediately stopped at the point where the cut was to terminate; then the starting lever would be pulled in the opposite direction and the entire heel portion would be operated on, except the short portion already cut. If, on the contrary, the succeeding heel had a shorter base than the one preceding, it would be necessary to operate the feed, before the table was moved back far enough for the sole edge to be engaged by the knife, to an extent sufficient to enable the edge portion, to be 75 beveled, to be engaged at an intermediate point. The table would then be moved back into position and the cut would be made up to one shoulder and then back to the other, as already described.

In some cases the breast edge or face of the heel is not exactly perpendicular to the central middle line of the heel, so that the sole would have to be beveled towards the shank farther on one side of the shoe than on the other. To provide for such conditions, the cross bar 78 is connected to the screw 80 by a pivot bolt 81, as shown in Fig. 13, so that, when the bar 78 is adjusted against a heel breast which is somewhat oblique to its center line, the bar may swing to a correspondingly oblique position, as shown in Fig. 7. While the bar 78 is pressed firmly against the heel breast, it cannot swing, so that, when either end engages the lever 76, it will move said lever to neutral position, and this will take place earlier or later according to the position of the cross bar 78. As a result, the cut will be terminated at each side of the shoe, at points corresponding to the position of the heel breast when placed in position on the shoe.

Various other adjustments may be made to adapt the machine to different conditions, for example, vertical adjustment of the heel and toe portions of the jack are sometimes necessary, to bring the shoe into the correct relation with the guide 46, the jack being provided with a well known means to permit such adjustment.

It will be understood that, while the illustrative embodiment, herein shown and described, is the best form of the invention of which I am at present aware, various

changes may be made therein without departing from the spirit and scope of my invention.

Having described the invention, what I claim as new and desire to secure by Letters Patent of the United States is:—

1. In a heel-seat fitting machine, a shoe support, a trimming knife movable to enter the sole of a shoe carried by said support from the tread surface of the sole at an acute angle thereto, means for operating said knife to sever surplus material by a succession of cuts along the periphery of the heel-seat of the sole, said shoe support being movable to transfer the point of operation of the knife along the work, and a crease guide occupying a fixed position with respect to the path of movement of said trimming knife and adapted to enter the rand crease to support the edge of the sole and to protect the upper.
2. A heel-seat fitting machine having, in combination, a shoe support, a movable trimming knife arranged to sever surplus material by a succession of cuts along the periphery of the heel-seat of the sole of a shoe carried by said support and to bevel the periphery of the heel-seat of the sole for the reception of a wood heel, a crease guide occupying a fixed position with respect to the path of movement of said trimming knife and adapted to enter the rand crease to support the edge of the sole and to protect the upper during the beveling, and means for holding the shoe against the crease guide as relative movement is produced between the shoe support and the knife to transfer the point of operation of the knife around the heel-seat portion of the sole.
3. In a heel-seat fitting machine, a shoe support, a movable knife arranged to bevel the heel-seat portion of the sole of a shoe at an angle suitable for the reception of a wood heel, a stationary crease guide occupying a fixed position with respect to the path of movement of said trimming knife and adapted to enter the rand crease to support the edge of the sole and to protect the upper, and means to move said shoe support under the guidance of said crease guide to transfer the point of operation of the knife around the periphery of the heel-seat portion of the sole, thereby to remove surplus material from the periphery of said heel-seat portion to bevel the same.

4. A machine for cutting on heels comprising a guide having sole-engaging and upper-engaging surfaces, and a vibrating knife movable to and from the sole-engaging surface of said guide in a direction oblique to the sole surface and transversely of its edge, said knife having a transversely disposed cutting edge for beveling the sole

edge portion and a shoulder-forming edge disposed at an angle to the transverse edge at each end.

5. In a heel-seat fitting machine, a shoe support, a trimming cutter, means for causing relative movement of said shoe support and said trimming cutter progressively to remove surplus material along the periphery of the heel-seat portion of the sole of a shoe carried by said support to fit the sole for the subsequent attachment of a wood heel, a crease plate adapted to enter the rand crease between the sole and the upper, means normally tending to hold said shoe in engagement with said crease plate during the progressive relative movement, and manually operated means operable to separate the trimming cutter and the shoe support.

6. In a heel-seat fitting machine, a shoe support, a trimming cutter, means for causing relative movement of said shoe support and trimming cutter to transfer the point of operation of the cutter around the heel-seat portion of the sole of the shoe, means set by engagement with a heel like that which is to be incorporated in the shoe arranged automatically to discontinue the relative movement of the shoe support and the cutter when the cutter is adjacent to the heel-breast line, and manually operated means arranged to produce relative movement in a reverse direction after the action of said automatic means.

7. A machine for cutting on heels comprising a knife movable in a predetermined path, a rand crease guide arranged in proximity to said path, a jack arranged to support a shoe with its sole in an oblique position with relation to said path, and in engagement with said guide, and means permitting swinging and longitudinal movement of said jack, to carry the periphery of the heel-seat portion of the sole into position for engagement by the knife.

8. A machine for cutting on heels comprising a knife movable in a predetermined path, a guide for the heel-portion of a shoe arranged in proximity to said path, a jack arranged to support the shoe with its sole in an oblique position with relation to said path, and in engagement with said guide, and means for automatically moving said jack longitudinally and rotatably to carry the periphery of the heel seat portion of the sole into position for engagement by the knife.

9. A machine for cutting on heels comprising a knife movable in a predetermined path, a guide for the heel-portion of a shoe arranged in proximity to said path, a jack arranged to support the shoe with its sole in an oblique position with relation to said path and in engagement with said guide, and a rotatably movable support in which said

- jack is slidably mounted arranged to permit the entire heel edge portion of the shoe sole to be carried into position to be operated on by said knife.
- 5 10. A machine for cutting on heels comprising a knife movable in a predetermined path, a guide for the heel-portion of a shoe arranged in proximity to said path, a jack arranged to support the shoe with its sole in an oblique position with relation to said path and in engagement with said guide, a rotatably movable support in which said jack is slidably mounted, and power-driven means arranged to engage said jack to cause compound swinging and sliding movements thereof.
- 10 15. A machine for cutting on heels, comprising a knife movable in a predetermined path, a guide for the heel-portion of a shoe arranged in proximity to said path, a jack arranged to support the shoe with its sole in an oblique position with relation to said path and in engagement with said guide, and having the heel end of its base portion shaped to approximate the contour of the heel portion of the shoe, a rotatable support on which the jack is mounted for sliding movement, a gear rack on said base portion, a gear arranged in mesh with said rack, and means for driving said gear to cause compound swinging and sliding movements of the jack.
- 20 25. A machine for cutting on heels comprising a knife movable in a predetermined path, a guide for the heel-portion of a shoe arranged in proximity to said path, a jack arranged to support the shoe with its sole in an oblique position with relation to said path and in engagement with said guide, power-driven means for causing sliding and swinging movement of the jack, to move the heel-portion of the sole into position for engagement by the knife, and means for automatically disconnecting said power-driven means from the source of power at predetermined points.
- 30 35. A machine for cutting on heels comprising a knife movable in a predetermined path, a guide for the heel-portion of a shoe arranged in proximity to said path, a jack arranged to support the shoe with its sole in an oblique position with relation to said path and in engagement with said guide, power-driven means for causing sliding and swinging movement of the jack, to move the heel-portion of the sole into position for engagement by the knife, and means for automatically disconnecting said power-driven means from the source of power at predetermined points.
- 40 45. A machine for cutting on heels comprising a knife movable in a predetermined path, a guide for the heel-portion of a shoe arranged in proximity to said path, a jack arranged to support the shoe with its sole in an oblique position with relation to said path and in engagement with said guide, power-driven means for causing sliding and swinging movement of the jack, to move the heel-portion of the sole into position for engagement by the knife, a heel-gage adjustably mounted on the jack and arranged to be set in positions corresponding to the length of the heel base, and means arranged to be engaged by said heel-gage to disconnect said power-driven means from the source of power.
- 50 55. A machine for cutting on heels comprising a knife movable in a predetermined path, a guide for the heel-portion of a shoe arranged in proximity to said path, a jack arranged to support the shoe with its sole in an oblique position with relation to said path and in engagement with said guide, power-driven means for causing sliding and swinging movement of the jack, to move the heel portion of the sole into position for engagement by the knife, a heel-gage adjustably mounted on the jack and arranged to be set in positions corresponding to the length of the heel base, and means arranged to be engaged by said heel-gage to disconnect said power-driven means from the source of power.
- 60 65. A machine for cutting on heels comprising a knife movable in a predetermined path, a guide for the heel-portion of a shoe arranged in proximity to said path, a jack arranged to support the shoe with its sole in an oblique position with relation to said path and in engagement with said guide, power-driven means for causing sliding and swinging movement of the jack, to move the heel portion of the sole into position for engagement by the knife, an abutment and a heel-breast-gage on said jack, said gage being adjustable to and from said abutment to engage the breast of a heel held thereagainst, and means arranged to be engaged by said gage to disconnect said power-driven means and its source of power automatically.
- 70 75. A machine for cutting on heels comprising a knife movable in a predetermined path, a jack arranged to support a shoe with its sole in an oblique position with relation to said path, and means for automatically moving said jack to carry the heel portion of a shoe thereon into position for engagement by said knife, to bevel the edge portion of the shoe sole about the heel portion thereof.
- 80 85. A machine for cutting on heels comprising a knife movable in a predetermined path, a jack arranged to support a shoe with its sole in an oblique position with relation to said path, automatic means for moving said jack in directions corresponding to the outline of the heel-portion of the sole, manually controlled means for starting said automatic means into operation, and a gage arranged to terminate the operation of said automatic means when the sole is moved to a position in which the knife engages it at a point corresponding to the location of the heel breast.
- 90 95. A machine for cutting on heels comprising a knife movable in a predetermined path, a jack arranged to support a shoe with its sole in an oblique position with relation to said path, automatic means for moving said jack in directions corresponding to the outline of the heel-portion of the sole, manually controlled means for starting said automatic means into operation, and a gage arranged to terminate the operation of said automatic means when the sole is moved to a position in which the knife engages it at a point corresponding to the location of the heel breast.
- 100 105. A machine for cutting on heels comprising a knife movable in a predetermined path, a guide arranged to position a shoe in predetermined relation to said path, a jack, a table for supporting said jack in position to hold a shoe thereon in engagement with said guide and the sole thereof in an oblique position with relation to said path, means permitting turning movement of the jack on the table, to feed its heel edge portion past said guide, and means permitting horizontal movement of said table to and from said guide.
- 110 115. A machine for cutting on heels comprising a knife movable in a predetermined path, a guide arranged to position the shoe in predetermined relation to said path, a jack, a table for supporting said jack in position to hold a shoe thereon in engagement with said guide and the sole thereof in an oblique position with relation to said path, and means permitting horizontal swinging and sliding movement of the jack on the table and simultaneous horizontal

sliding movement of the table to feed the heel edge portion of the shoe into operative relation to said knife.

19. A machine for cutting on heels comprising a knife movable in a predetermined path, a guide arranged to position a shoe in predetermined relation to said path, a jack, a table for supporting said jack in position to hold a shoe thereon in engagement with said guide and the sole thereof in an oblique position with relation to said path, power actuated means for horizontally moving the jack longitudinally and rotatably on said table, and manually controlled means for moving said table horizontally.

20. A machine for cutting on heels comprising a knife movable in a predetermined path, a guide arranged to position a shoe in predetermined relation to said path, a jack, a table for supporting said jack in position to hold a shoe thereon in engagement with said guide and the sole thereof in an oblique position with relation to said path, power-actuated means for moving the jack on the table to feed the heel edge portion of the shoe past said guide, and means to move the table to and from the guide as the jack is rotated.

21. A machine for cutting on heels comprising a knife movable in a predetermined path, a guide for a shoe arranged adjacent to said path, a jack for holding the heel portion of the shoe in engagement with said guide with the sole thereof in oblique relation to said path, and means for causing universal movement of the jack approximately in the plane of the shoe bottom, to feed the heel portion of the shoe past said guide, as it is held in engagement therewith.

22. A machine for cutting on heels comprising a knife movable in a predetermined path, a guide for a shoe arranged adjacent to said path, a jack for holding the heel portion of the shoe in engagement with said guide, with the sole thereof in oblique relation to said path, means for causing a turning movement of the jack about an axis disposed approximately perpendicular to the shoe bottom, and means for moving the jack towards and from said guide as it is turned.

23. A machine for cutting on heels comprising a knife movable in a predetermined path, a guide for a shoe arranged adjacent to said path, a jack for holding the heel portion of the shoe in engagement with said guide, with the sole thereof in oblique relation to said path, means to move the jack longitudinally and rotatably, and independent means to move the jack towards and from said guide to hold the same in contact therewith.

24. A machine for cutting on heels comprising a knife movable in a predetermined path, a guide for a shoe arranged adjacent

to said path, a jack for holding the heel portion of the shoe in engagement with said guide, with the sole thereof in oblique relation to said path, means to cause swinging and sliding movements of the jack to move the sole heel portion to be operated on past said guide, and means constantly tending to move the jack towards said guide to hold the shoe in yielding engagement therewith.

25. A machine for cutting on heels comprising a knife movable in a predetermined path, a guide for a shoe arranged adjacent to said path, a jack for holding the heel portion of the shoe in engagement with said guide, with the sole thereof in oblique relation to said path, a table for supporting said jack manually movable towards and from said guide, and power-actuated means arranged to move the jack rotatably and slidably on the table in the different positions of the latter.

26. A heel-seat fitting machine having, in combination, a knife movable in a predetermined path, a guide arranged in fixed relation to said path, a table movable to and from said guide, a support carried by said table and arranged to swing about an axis extending vertically to the plane of movement of the table, and a jack mounted to slide on said support in directions parallel to said plane of movement to permit a shoe carried by said jack to be held against said guide in position to be operated on by said knife throughout the length of the heel portion of its sole.

27. In a machine for use in making shoes, in combination, means to perform an operation on a partly-finished shoe to prepare it for the incorporation of a shoe-part, and a device to control the operation of said means according to a characteristic of the particular part which is to be incorporated in the shoe as determined by engagement therewith.

28. In a machine for use in making shoes, in combination, means to position a partly-finished shoe and to operate thereon according to a separate shoe part which is to be an integral part of the finished shoe, a device to engage and be set by the particular separate part which is to enter into the particular shoe being operated upon, and connections therebetween so that the operation of said means is controlled by said device.

29. In a machine of the class described, in combination, means to prepare a shoe for the addition of a heel, a gage to be set by the heel which is to be added, and a connection from the gage to control the preparation of the shoe.

30. In a heel-seat fitting machine, in combination, means including trimming and positioning devices to fit the heel-seat of a shoe for the addition of a heel, a measuring

device to determine the size of the seat of the heel to be added, and a connection from the measuring device to the positioning device to control the fitting operation to fit 5 the shoe to the particular heel so measured.

31. In a heel-seat fitting machine, in combination, a trimming device and a sole-positioning device co-operating to trim a sole to fit a heel, a gage to measure the heel to 10 be fastened upon the particular sole being operated upon, and means operated by the gage in its movements to cause the trimming to fit the sole according to the heel so measured.

32. In a machine of the class described, in combination, means including positioning and operating devices to prepare a part of a shoe for the superposition of another part, and a device spaced therefrom to measure 20 a characteristic of said second part and control the operation of the preparing means according to such measurement.

33. In an apparatus for use in making shoes, in combination, a tool to operate on a 25 partly-finished shoe, means to determine the relative positions of a shoe and the tool, a device spaced therefrom to engage and be set by a separate part which is afterwards incorporated in the shoe, and a connection between said device and said means to cause the tool to operate differently on different shoes according to the setting of 30 said device.

34. A heel-seat fitting machine comprising, in combination, cutting means to remove the surplus edge of the sole of a shoe from the heel-breast line rearwardly, a support for a shoe being operated on thereby, and a device set by engagement with a heel like 40 that for which the heel seat is to be fitted to vary the relative position of the cutting means and the support so that the heel-breast line will be located according to the size of the heel.

35. A machine for use in making shoes comprising, in combination, a knife to make a cut on a shoe at the heel-breast line, a support to present the work thereto, and means spaced therefrom engaging a separate tem- 50 plet to vary the relative position of the knife and the support to determine the heel-breast line according to the templet.

36. A machine for use in making shoes comprising, in combination, means to operate on a part of a shoe throughout a portion of its length, members to engage opposite sides of a pattern, and connections to vary the length of the portion operated upon according to the distance between said members.

37. A machine for use in making shoes comprising, in combination, a support for a shoe, cutting and positioning means, and pattern controlled means for determining the 60 relative position of said cutting and position-

ing means to fit the heel-seat of the shoe for the addition of a heel.

38. A machine for use in making shoes comprising, in combination, a tool to operate on a shoe, a support to present a shoe thereto, and means controlled by a dimension of a shoe part to vary the position of the support thereby to adjust the position of the shoe with reference to the tool.

39. A heel-seat fitting machine of the type 75 having a knife to trim the sole of a shoe to fit a heel and comprising, in combination, a support for a shoe, a device to engage a shoe supported thereby to position it relatively to the knife to determine the breast line, and a member set by engagement with a heel to vary the position of said device according to the heel engaged thereby.

40. A heel-seat fitting machine comprising, in combination, shoe positioning and 85 trimming devices to fit the heel seat of a sole to receive a heel, means relatively to adjust said devices to change the size of the heel seat fitted thereby, and means to engage opposite sides of a heel to measure its size 90 and connected with the first-named means to determine the proper adjustment of said means.

41. A heel-seat fitting machine comprising, in combination, a trimming cutter and 95 a shoe support relatively movable progressively to remove waste material from the periphery of the sole of a shoe on the support rearwardly of the heel breast line, a stop to determine the length of the part of 100 the sole operated on by the cutter, a fixed abutment for engaging one end of the heel, and a heel-engaging member for the other end of the heel, connected to the stop to set the machine to trim different shoes differently according to the sizes of different heels engaged by the member.

42. A heel-seat fitting machine having, in combination, a cutter for trimming surplus material from the periphery of the heel-seat portion of the sole of a shoe, means for positioning a shoe in definite relation to said cutter, means for positioning a heel such as is to be attached to the shoe in a predetermined position at a substantial distance from the 115 heel-seat of the shoe, and means for gaging the extent of the trimming operation from the heel thus positioned.

43. A heel-seat fitting machine having, in combination, an oscillating chop knife, and 120 means for positioning a shoe with the tread surface of its sole inclined relatively to said knife constructed and arranged to allow relative movement of the shoe and said knife to transfer the point of operation of the knife along the periphery of the heel-seat portion of the sole of the shoe, thereby beveling the peripheral portion of the heel-seat of the sole and removing surplus material therefrom.

44. A heel-seat fitting machine having, in combination, a cutter for trimming surplus material from the periphery of the heel-seat portion of the sole of a shoe, a work support arranged to present a shoe in operative relation to said cutter, means for positioning a heel such as is to be attached to the shoe in a predetermined position at a substantial distance from the heel-seat of the shoe, and means for gaging the extent of the trimming operation from the heel thus positioned.

45. A machine for use in the manufacture of shoes comprising means for operating upon a shoe part, a support arranged to present a shoe part to said operating means, a support for a second shoe part, and means for limiting the extent of the operation of the operating means upon the first named shoe part controlled by the second shoe part.

46. In a heel-seat fitting machine, a shoe support, a trimming cutter, means for causing relative movement of said cutter and said shoe support to transfer the point of operation of the cutter around the heel-seat portion of the sole of a shoe on said support, and means set by engagement with a heel such as the heel which is to be incorporated in the shoe, constructed and arranged to control the relative movement of said shoe support and said cutter lengthwise of the shoe so that the trimming action of the cutter extends along the sides of the heel-seat portion of said sole to points which may be at different distances from the rear end of the sole in accordance with the size and shape of the heel.

47. In a machine of the character described, a shoe support, a trimming cutter, means for causing relative movement of said shoe support and said trimming cutter progressively to bevel the periphery of the heel-seat portion of the sole of a shoe on said support, and means set by engagement with a heel such as the heel which is to be incorporated in the shoe constructed and arranged to stop the relative movement of the shoe support and the trimming cutter at points which may be located at different distances from the rear end of the sole along the inside and outside of the shoe corresponding to the inside and outside length of the heel.

48. A heel-seat fitting machine having, in combination, a cutter turning on an axis and provided upon each side thereof with a radial cutting edge disposed crosswise of said axis and with an outer cutting edge disposed lengthwise of said axis and traveling a path between the paths of said side cutting edges, and means for supporting a shoe sole with its tread surface inclined relatively to the path of movement of said cutter whereby the periphery of the heel-seat portion of the sole is beveled by the cutter.

49. A heel-seat fitting machine having, in combination, a work support, a knife hav-

ing a plurality of angularly related cutting edges, and means for moving the knife through a path inclined relatively to the surface of the heel-seat of the sole of a shoe upon the support to cause the knife to bevel the portion of the periphery of the sole operated upon thereby.

50. A heel-seat fitting machine having, in combination, a work support, a knife having angularly related cutting edges, and means for causing relative movement of the knife and the work support to cause the knife to bevel the portion of the periphery of the sole operated upon thereby and to form a heel-breast receiving shoulder at the heel-breast line of the sole.

51. A heel-seat fitting machine having, in combination, a chop knife, and means for positioning a shoe in definite relation to the knife with the sole of the shoe inclined relatively to the path of movement of the knife constructed and arranged to permit relative movement of the shoe and the path of movement of the knife to transfer the point of operation of the knife along the periphery of the heel-seat portion of the sole of a shoe to remove surplus material from and to bevel the peripheral portion of the heel-seat of the sole.

52. A heel-seat fitting machine having, in combination, a chop knife, means for oscillating the knife, a crease plate arranged to enter the rand crease of a shoe to position the shoe with the tread surface of its sole inclined relatively to the path of movement of the knife, and means for causing relative movement of the shoe and the path of movement of the knife to transfer the point of operation of the knife along the periphery of the heel-seat portion of the sole of the shoe, thereby beveling and removing surplus material from the periphery of the heel-seat portion of the sole.

53. In a machine of the character described, a support for the sole of a shoe, and an oscillating cutter movable in a path oblique to the tread surface of said sole, said cutter being provided with a cutting edge disposed in the general direction of the axis of movement of the cutter and with side cutting edges operable in planes substantially normal to the axis of movement of the cutter, whereby said cutter may be operated to make a gouging cut through the periphery of said sole whereby to bevel a portion of the same.

54. In a machine of the character described, a support for a shoe sole, and a channel-shaped oscillating cutter arranged to enter the sole at its surface and moving in a path oblique to the plane of the surface of said sole passing through the peripheral portion of said sole, thereby to form a bevel and completely to remove a chip of surplus material.

55. A heel-seat fitting machine having, in combination, a support for a shoe, and an oscillating knife arranged to cut from the tread surface through the sole of the shoe at an inclination to the surface of the sole, said machine being constructed and arranged to provide relative movement between the sole support and the path of movement of the oscillating knife, thereby to cause the knife by cutting successive chips adjacent to one another along the periphery of the sole to remove surplus material from and to bevel a portion of said periphery. 5. In a heel-seat fitting machine a shoe support, a knife, means for oscillating said knife in a path at a substantial inclination to the tread surface of the heel-seat portion of the sole of a shoe upon said support, and means for causing relative movement of said shoe support and said knife to transfer the point of operation of the knife along the periphery of the sole. 6. In a heel-seat fitting machine, a shoe support, an oscillating knife provided with angularly related cutting edges, and means for causing relative movement of said shoe support and said knife to transfer the point of operation of the knife around the periphery of the rear end of the sole of the shoe so as to remove surplus material from the heel-seat portion of the sole, thereby to form a bevel around said heel-seat portion and a shoulder adjacent to said beveled portion at the heel-breast line. 7. In a heel-seat fitting machine, a shoe support, an oscillating knife provided with a plurality of cutting edges, said cutting edges comprising an intermediate edge and lateral angularly related edges, and means for causing relative movement of said shoe support and said knife to transfer the point of operation of the knife around the heel-seat portion of the sole of the shoe from the heel-breast line at one side of the sole around the rear end of the sole to the heel-breast line at the other side of the sole, thereby to bevel said heel-seat portion and to form shoulders at the heel-breast line adjacent to said beveled portion. 8. In a heel-seat fitting machine, a shoe support, an oscillating channel-shaped knife movable in a path oblique to the tread surface of the sole of the shoe, means causing relative movement of said knife and said shoe support to transfer the point of operation of the knife from the heel-breast line at one side of the sole around the rear end of the sole to the heel-breast line at the other side of the sole to bevel the heel-seat of the sole and to form shoulders adjacent to said beveled portion, and means to control the position of said shoulders at opposite sides of the sole. 9. In a heel-seat fitting machine, a shoe support, an oscillating trimming knife mov- able in a path substantially oblique to the tread surface of the sole of the shoe, a crease guide adapted to enter the rand crease to support the edge of the sole arranged in a plane substantially parallel to the sole of the shoe to protect the upper at a point adjacent to the path of operation of said trimming knife, and means for causing relative movement of said shoe support and said knife under the control of said crease guide to transfer the point of operation of the knife along the periphery at the rear end of the sole thereby to bevel the heel-seat portion of the sole, removing surplus material by a succession of cuts as the trimming action progresses. 10. In a machine of the character described, a rand crease guide having a thin edge adapted to be inserted in the rand crease to support the periphery of a sole of a shoe and to protect the upper, said guide being provided with a sharp edge, and an oscillating tool operable to remove surplus material from the periphery of the sole of said shoe, said tool being constructed and arranged to co-operate with the sharp edge upon said rand crease guide to make a shearing cut. 11. In a heel-seat fitting machine, a rand crease guide having a thin edge adapted to be inserted in the rand crease of a shoe to support the edge of the sole of said shoe and to protect the upper, said guide being provided with a sharp edged recess, and an oscillating tool arranged to cut through the periphery of the sole of said shoe to remove surplus material therefrom, the path of movement of said tool being so disposed with reference to the rand crease guide that the edge of the tool passes the sharp edge of the recess in the rand crease guide to make a shearing cut. 12. In a heel-seat fitting machine, a rand crease guide having a thin edge adapted to be inserted in the rand crease of a shoe to support the edge of the sole of said shoe and to protect the upper, said guide having a sharp edged recess provided with angularly related edges, and an oscillating knife arranged to cut through the periphery of the sole overlying said rand crease guide to remove surplus material therefrom, said tool being provided with angularly related cutting edges and having its path of movement so disposed with reference to the rand crease guide that the edges of the tool co-operate with the sharp edges of the recess in the guide to complete the cutting action with a shearing cut. 13. That improvement in methods of heel seat fitting which comprises positioning a heel such as is to be attached to a shoe in a predetermined position at a substantial distance from the heel seat of the shoe, and utilizing the heel thus positioned as a gage to

determine the extent of the heel seat fitting operation.

65. That improvement in methods of heel seat fitting which comprises positioning a heel such as is to be attached to a shoe in a predetermined position relatively to the heel seat of the shoe, trimming surplus material from the heel seat portion of the sole of the shoe, and controlling the extent of the trimming operation by contact with opposite faces of the heel.

66. That improvement in methods of heel seat fitting which comprises positioning a heel such as is to be attached to a shoe in a predetermined position at a substantial distance from the heel seat of the shoe, and utilizing the forward end of the heel thus positioned to control the forward extent of the trimming operation during the relative movement of the shoe and heel seat trimming instrumentalities.

67. That improvement in methods of con-

trolling the trimming of the heel seat of a sole to prepare the heel seat to receive a heel, which comprises spacing a heel a substantial distance from the sole, trimming surplus material from the heel seat portion of the sole, and utilizing the heel while so spaced to control the forward extent of the trimming operation on the sole.

68. That improvement in methods of heel-seat fitting which comprises positioning a heel having its breast surface extending further forward on one side than on the other in a predetermined position relatively to the heel-seat of the sole of a shoe, trimming surplus material from the heel-seat portion of the sole of a shoe, and controlling the forward extent of the trimming by gaging from the rear and the two ends of the breast surface of the heel.

In testimony whereof, I have signed my name to this specification.

RICHARD FRANCIS JOYCE.
